METHOD OF MAKING A TUBULAR ARTICLE

Thomas A. Graham, San Francisco, Calif., assignor to National Tube Company, a corporation of New Jersey

Application May 13, 1937, Serial No. 142,455

6 Claims. (Cl. 29—156)

This invention particularly relates to a method of making a tubular article that is provided with an outwardly extending drip lip or fin in the circumference thereof.

5 An object of this invention is to provide a practical, efficient method of making tubular articles of this class.

The above and further objects will become apparent by referring to the following description and the accompanying drawings in which:

10 Figure 1 is a longitudinal sectional elevation of one embodiment of apparatus for performing one of the steps of my invention;

Figure 2 is a transverse sectional elevation on line II—II of Figure 1;

Figure 3 is a transverse sectional elevation on line III—III of Figure 1;

Figure 4 is a longitudinal sectional elevation of one embodiment of apparatus for performing a further step of my invention;

Figure 5 is a transverse sectional elevation on line V—V of Figure 4; and,

Figure 6 is a transverse sectional elevation of the finished tubular article.

25 Referring more particularly to the drawings the numeral 2 designates a tubular blank or tube which preferably has previously been cold drawn to the equivalent round size desired in a heat transfer conduit or tubular article 4 to be made therefrom. The tube 2 can be drawn by the standard lead coated or other suitable method and ordinarily should have a wall slightly thicker than that desired in the tubular article 4.

To form a drip lip or fin in the wall of the 30 tube 2, the tube 2 is preferably drawn through the pass formed by a die 6 and a mandrel 8. The pass formed by the die 6 and the mandrel 8 is designed to fabricate an outwardly extending drip lip or fin 10, which is substantially V-shaped in section, in the wall of the tube 2 and reduce the diameter thereof but keep the remainder of the tube 2 substantially round. The fin 10 preferably extends radially from the tube 2 and, as the tube 2 was positively held 35 when drawn through the die 6 and the mandrel 8, the fin 10 is straight and longitudinally directed, as desired. Ordinarily the length of the periphery of the tube 2 is not changed when the tube is drawn over the mandrel 8. After the 40 fin 10 is formed in the tube 2, the lead on the tube (if any) is removed and the tube is heat treated, straightened, cut and finished in the ordinary manner.

45 After the tube has been treated in the above described manner a second tubular blank or tube

12 is disposed therein by any suitable means. The tube 12 has preferably been drawn by the standard lead coated method to an outside diameter but slightly smaller, for example one sixteenth of an inch, than the inside diameter 5 of the tube 2. Also, any lead on the tube 12 should be removed and the tube finished by a process similar to that given the tube 2. The tube 12 is provided with a smooth circular bore which is substantially the size desired in the 10 finished tubular article 4. Both tubes are preferably made from stainless steel, as it does not easily corrode and, in addition, is a good heat conductor.

To make the tube 12 integral with the tube 15 2 and form the tubular article 4, an expanding mandrel 14 or other suitable means is drawn through the tube 12 while the tube 2 is held thereon. The mandrel 14 is adapted to expand the tube 12 until the outer surface thereof bears 20 upon and preferably slightly expands the outer tube 2. Lubricating means, such as aluminum paint, is supplied to the mandrel 14 during the drawing operation. The inner tube 12 must be expanded a sufficient amount so that its outer 25 surface bears upon all of the inside surface of the outer tube 2 except for the portion thereof forming the fin 10. As the tubes are in tight contact a good heat transfer relationship is 30 established therebetween. The expanding mandrel 14 is adapted to leave a smooth circular bore in the tube 12 after it has been drawn there-through.

The surface of the outer tube 2 may be polished, if desired, and the tubes cut or finished in 35 any given manner to prepare the tubular article 4 for use.

The tubular article 4 is particularly adapted for use in liquid coolers or regenerators or chemical apparatus in which cleanliness is required. 40 The surfaces of the finished article are not effected by ordinary corroding agents but, if any impurities do collect or remain thereon, both the inner and outer surfaces of the tubular article 4 are easily cleaned.

In use, a plurality of the tubular articles 4 are to be horizontally positioned and placed immediately above or below one another in the same vertical plane. The fins 10 must extend downwardly from the tubular articles 4. Then 50 any liquid that is permitted to flow onto the uppermost one of the tubular articles 4 flows over the maximum amount of surface area of each tubular article as the liquid clings to the circumference thereof until led to flow therefrom by 55

- the fin 10. The liquid then drips or flows onto the top of the tubular article immediately below that fin so that, due to the maximum contact obtained, a maximum amount of heat can be transferred between the inner and outer surfaces of the tubular articles 4. Of course, a fluid is contained in the bores of the tubular articles 4 when a liquid is permitted to flow over the outer surfaces of the tubular articles 4.
- 10 The tubular article 4 has been tested and found to readily and efficiently exchange heat between the inner and outer surfaces thereof. The liquid to be heated or cooled can be placed in contact with either surface of the tubular article 4.
- 15 While I have shown and described one form of apparatus for carrying out the steps of my method, it will be understood that I am not limited thereto, since various modifications thereof may be made without departing from the scope of my 20 invention as defined by the following claims.

I claim:

1. That method of manufacturing a heat transfer conduit having a smooth circular inner bore and a longitudinally extending drip lip or fin in the circumference thereof which comprises forming a tube having a radially outwardly extending drip lip or fin in its wall extending longitudinally and continuously the length of the tube, the drip lip or fin being substantially V-shaped in section, disposing a second tube having an outside diameter but slightly smaller than the inside diameter of the first mentioned tube in the bore of the first mentioned tube, and expanding the inner tube until the outer surface thereof bears upon and slightly expands the outer tube so as to slightly spread the V-shaped drip lip in the wall thereof so that said inner tube is securely held within said outer tube and all of the surface of the outer tube except for the portion thereof forming the drip lip or fin being in tight heat transfer relation with the surface of the inner tube.
2. That method of manufacturing a heat transfer conduit having a smooth circular inner bore and a longitudinally extending drip lip or fin in the circumference thereof which comprises forming a tube having substantially the equivalent round size desired in the heat transfer conduit, fabricating a radially directed outwardly extending drip lip or fin in its wall extending longitudinally and continuously the length of the tube, disposing a second tube having an outside diameter but slightly smaller than the inside diameter of the first mentioned tube and a circular bore of substantially the size desired in the finished conduit in the bore of the first mentioned tube, and expanding the inner tube until the outer surface thereof bears upon and slightly expands the outer tube so as to slightly spread the outwardly extending drip lip in the wall thereof so that said inner tube is securely held within said outer tube.
3. That method of manufacturing a heat transfer conduit having a smooth circular inner bore

and a longitudinally extending drip lip or fin in the circumference thereof which comprises forming a tube having substantially the equivalent round size desired in the heat transfer conduit, fabricating a longitudinally and continuously directed radially outwardly extending drip lip or fin in the wall of the tube, the drip lip or fin being substantially V-shaped in section, disposing a second tube having an outside diameter but slightly smaller than the inside diameter of the 10 first mentioned tube and a circular bore of substantially the size desired in the finished conduit in the bore of the first mentioned tube, expanding the inner tube until the outer surface thereof bears upon and slightly expands the outer tube 15 so as to slightly spread the V-shaped drip lip in the wall thereof so that said inner tube is securely held within said outer tube and all of the surface of the outer tube except for the portion thereof forming the drip lip or fin being in tight heat 20 transfer relation with the surface of the inner tube, and finishing the surface of the outer tube.

4. The method of making a tubular article which comprises forming a stainless steel tube by passing the tube between a mandrel and a die to 25 form a radially outwardly projecting rib-like drip-lip in its wall, extending longitudinally substantially the length of said tube for directing the flow of liquids therefrom, placing a second smaller stainless steel tube within said first mentioned 30 tube and passing a mandrel through said second mentioned tube to expand the same so that the entire outer surface of the last named tube is in close contact with the inner surface of the first 35 named tube.

5. The method of making a tubular article which comprises providing an outer tube having an outwardly projecting drip lip portion formed in the wall thereof, disposing a second tube within said outer tube, and expanding said inner 40 tube until it contacts the inner wall of said outer tube and slightly expands said outer tube so as to slightly spread the outwardly projecting drip lip portion in the wall thereof so that said inner tube will be securely held within said outer tube. 45

6. The method of making a tubular unit for use in liquid regenerators and the like which comprises forming a metallic outer tube with a radially outwardly projecting rib-like drip lip portion in its wall extending longitudinally and 50 continuously substantially the length thereof, disposing a second tube within said outer tube after it is so formed, and drawing a mandrel through said inner tube to expand the same until it contacts the inner surface of the outer tube and slightly expands said outer tube so as to slightly spread the projecting rib-like drip lip portion in the wall thereof so that said inner tube is securely held within said outer tube and in close contact with substantially the entire inner surface of said 55 outer tube.

THOMAS A. GRAHAM.
